CLAIM

The ornamental design for a wristband timer watch, as shown and described.

DESCRIPTION

FIG. 1 is a front elevational view of my new design with the phantom lines in the watch display depicting environmental structure and forming no part of the claimed design;

FIG. 2 is a back elevational view thereof;

FIG. 3 is a left side elevational view thereof;

FIG. 4 is a top plan view thereof;

FIG. 5 is a bottom plan view thereof; and,

FIG. 6 is a right side elevational view thereof.
